CHILD'S CHAIR

Matthias A. Lydon, Des Plaines, Ill.

Application September 1, 1949, Serial No. 4,802

Term of patent 7 years

(Cl. D15—8)

To all whom it may concern:

Be it known that I, Matthias A. Lydon, a citizen of the United States, residing at Des Plaines, in the county of Cook and State of Illinois, have invented a new, original, and ornamental Design for a Child's Chair, of which the following is a specification, reference being had to the accompanying drawing, forming a part thereof.

In the drawing:

Fig. 1 is a perspective view of a child's chair looking toward one side, showing my new design; and

Fig. 2 is a perspective view looking toward the front.

I claim:

The ornamental design for a child's chair, as shown.

MATTHIAS A. LYDON.
